UNITED STATES PATENT OFFICE.

RANSOM Y. BOVEE, OF MAYWOOD, ILLINOIS, ASSIGNOR TO BOVEE NOVELTY COMPANY, OF MAYWOOD, ILLINOIS, A CORPORATION OF ILLINOIS.

FOLDING COMBINATION TOILET ARTICLE.

Original application filed June 2, 1922, Serial No. 565,354. Divided and this application filed March 19, 1923, Serial No. 625,955.

To all whom it may concern:

Be it known that I, RANSOM Y. BOVEE, a citizen of the United States, residing at Maywood, in the county of Cook and State 5 of Illinois, have invented certain new and useful Improvements in Folding Combination Toilet Articles, of which the following is a specification.

This application is a division of my original application Serial No. 565,354, filed June 2, 1922, and the present invention relates more particularly to an improved article of this character embodying a plurality of toilet articles all adapted to be compactly 15 folded into a casing when not in use, and which casing embodies a portion which is adapted to be employed for containing memorandum sheets or to constitute a storage compartment for postage stamps and the 20 like, the sheets being detachably secured in position so that they may be removed when desired and additional sheets replaced.

To the attainment of these ends and the accomplishment of other new and useful objects as will appear, the invention consists 25 in the features of novelty in substantially the construction, combination and arrangement of the several parts hereinafter more fully described and claimed and shown in the accompanying drawing illustrating this invention, and in which—

Figure 1 is a view in elevation of one side of a device of this character, showing the articles in a partially unfolded position with 35 respect to the casing.

Figure 2 is a side elevation of one face of the casing with parts removed.

Figure 3 is a sectional view taken on line 3—3, Figure 2.

Figure 4 is an enlarged sectional view taken on line 4—4, Figure 1, and showing the parts in a folded position.

Referring more particularly to the drawing, the numeral 10 designates generally a 45 casing of any desired size and configuration and constructed of any suitable material. The casing is provided with an eyelet 11 at the open end thereof, by means of which it may be suspended from a suitable supporting device 12.

Pivottally connected at one end of the casing is a combined comb and brush 13, adapted to be folded into and out of the casing. Pivottally connected, preferably at the other

end of the casing, are a plurality of toilet 55 articles 14, 15, 16, 17 and 18, all of which are adapted to be independently folded into and out of the casing.

The wall 19 of the casing is provided with a receptacle 20 open through the face thereof, of a considerable area and is adapted to receive cards or sheets 21, which may be independently removed or detached. These cards or sheets may be formed of any suitable material so as to serve as memoranda 65 sheets or for the storage of postage stamps or the like therebetween. An additional sheet 22, preferably constructed of celluloid or similar material is arranged in the receptacle 20 and serves as a cover for the sheets 70 21 and also for the purpose of receiving memoranda which latter may be erased from the sheet when desired. All of the sheets are detachably secured within the receptacle 20 by means of lugs 23 having heads thereon, and which lugs are preferably formed from the bottom of the compartment and engage in suitable apertures 24 in the cards or sheets. The lugs 23 are preferably located at one end of the compartment 80 20 and the cards or sheets are preferably of a width somewhat less than the width of the receptacle 20, so as to form a pencil holding compartment or space 25, in which a pencil 26 is adapted to be held. 85 The pencil is held against displacement by means of tongues 27, preferably formed from the bottom of the receptacle and bent into shape, and an opposed spring tongue 28 is also formed preferably from the bottom 90 of the receptacle and arranged intermediate the tongues 27 to co-operate therewith for yieldingly engaging the pencil and for removably securing the pencil in the receptacle 20.

The pencil 26 is preferably provided with a reduced portion 29, into which the tongue 28 projects.

A closure 30 is hingedly connected as at 31 with the wall 16 and is of a size to completely close the receptacle 20, the closure being secured in a closed position, preferably by means of a tongue 32 formed from a portion of the closure and which tongue co-operates with a portion of the spring 105 tongue 28.

A calendar 33 is arranged on the inner face of the closure 30.

The implements 13, 14, 15, 16, 17 and 18 are adapted to be folded into and out of casing 10 without interfering with the compartment 20, the closure, or the contents 5 thereof.

When it is desired, the closure 30 may be opened to permit access to the compartment 20, while all of the implements are in a folded position with respect to the case 10. 10 It will be manifest that with this improved construction a compact device will be provided and the contents of the receptacle 20 may serve for memoranda purposes, access being readily had thereto without interfering with any of the other parts of the device. 15

The pencil 26 may be readily removed for use and as readily replaced and the sheets 21 and 22 may also be readily removed when 20 desired, or portions of the sheets 21 may be detached without detaching the other sheets.

While the preferred form of the invention has been herein shown and described it is to be understood that various changes may be 25 made in the details of construction, and in the combination and arrangement of the several parts, within the scope of the claims, without departing from the spirit of this invention.

30 What is claimed as new is:—

1. An article of the character described embodying a casing, a plurality of articles pivotally connected therewith and adapted to be folded into and out of the casing, a 35 portion of one wall being shaped to form an open receptacle, one or more upstanding lugs integral with and formed from a portion of the casing wall and disposed within the receptacle, cards or sheets detachably 40 engaging the lugs and disposed within the receptacle, and a closure for the receptacle.

2. An article of the character described embodying a casing, a plurality of articles pivotally connected therewith and adapted 45 to be folded into and out of the casing, a portion of one wall being shaped to form an open receptacle, one or more upstanding lugs integral with and formed from a portion of the casing wall and disposed within 50 the receptacle, cards or sheets detachably engaging the lugs and disposed within the receptacle, a closure for the receptacle, and a calendar carried by the closure.

3. An article of the character described

embodying a casing, a plurality of articles 55 pivotally connected therewith and adapted to be folded into and out of the casing, a portion of one wall being shaped to form an open receptacle, one or more upstanding lugs integral with and formed from a portion of the casing wall and disposed within the receptacle, cards or sheets detachably 60 engaging the lugs and disposed within the receptacle, a pencil holder within the receptacle, and a closure for the receptacle. 65

4. An article of the character described embodying a casing, a plurality of articles pivotally connected therewith and adapted to be folded into and out of the casing, a portion of one wall being shaped to form an 70 open receptacle, one or more upstanding lugs integral with and formed from a portion of the casing wall and disposed within the receptacle, cards or sheets detachably engaging the lugs and disposed within the 75 receptacle, a pencil holder within the receptacle, and a closure for the receptacle, said pencil holder being formed by opposed spring lip portions.

5. An article of the character described 80 embodying a casing, a portion of one wall being shaped to form an open receptacle, one or more upstanding headed lugs integral with and formed from a portion of the bottom of the receptacle and disposed within 85 the receptacle, cards or sheets detachably engaging the headed lugs and disposed within a receptacle, and a closure for the receptacle.

6. An article of the character described 90 embodying a casing, a portion of one wall being shaped to form an open receptacle, one or more upstanding headed lugs formed from a portion of the bottom of the receptacle and disposed within the receptacle, cards 95 or sheets detachably engaging the headed lugs and disposed within the receptacle, one or more additional and opposed spring lip portions disposed within the receptacle for holding a pencil, a closure for the receptacle, and means on the closure co-operating 100 with one of the said spring lips, constituting a fastening for the closure.

In testimony whereof I have signed my name to this specification, on this 14th day 105 of March, A. D. 1923.

RANSOM Y. BOVEE.
